UNITED STATES PATENT OFFICE.

CONSTANT VAN DE WALL, OF NEW YORK, N. Y., ASSIGNOR TO WAITE GRASS CARPET COMPANY, OF OSHKOSH, WISCONSIN, A CORPORATION OF WISCONSIN.

DESIGN FOR A GRASS RUG.

54,791.

Specification for Design.

Patented Mar. 23, 1920.

Application filed November 1, 1919. Serial No. 335,194. Term of patent 7 years.

To all whom it may concern:

Be it known that I, CONSTANT VAN DE WALL, a subject of the Queen of Holland, residing at New York, in the county of New York and State of New York, have invented a new, original, and ornamental Design for Grass Rugs, of which the following is a specification, reference being had to the accompanying drawing, forming part thereof, which shows a rug in plan view, embodying my new design.

I claim:

The ornamental design for a grass rug, substantially as shown.

CONSTANT VAN DE WALL.
